UNITED STATES PATENT OFFICE.

CHARLES S. BUSHNELL, OF ROCHESTER, NEW YORK, ASSIGNOR TO GENERAL RAILWAY SIGNAL COMPANY, OF GATES, NEW YORK, A CORPORATION OF NEW YORK.

TRAIN CONTROL.

Application filed April 17, 1922. Serial No. 553,624.

To all whom it may concern:

Be it known that I, CHARLES S. BUSHNELL, a citizen of the United States of America, residing at Rochester, in the county of Monroe and State of New York, have invented certain new and useful Improvements in Train Controls, of which the following is a specification.

This invention relates to train control systems, and more particularly to means for communicating controlling influences from the trackway to the vehicle inductively.

In systems for automatically controlling trains and for displaying signals in the cab of a railway vehicle, it is necessary to communicate controlling influences from the trackway to the moving vehicles. Such communication is preferably accomplished through an intervening air gap, rather than by physical contact between devices on the vehicle and cooperating devices along the track, and it has been found expedient to communicate such influences inductively, that is, by action taking place through an intervening air gap by magnetic or electromagnetic induction. With such an inductive system, consideration must be given to the fact that many railroads require that the space between the track rails almost to the top of the ties shall be kept clear in order to permit the flangers of snow plows to remove snow from between the rails. Full compliance with this requirement ordinarily results in a large air gap between the car-carried device and the trackway device, in those cases where the trackway device is located between the track rails, because the track element can not extend much, if any, above the top of the ties, while the car element can not extend below the top of the rails, otherwise it would not clear the rails at switches, crossings, and the like. It is desirable, however, from the standpoint of efficiency and reliability in operation, to work through as small an air gap as the working clearances will permit.

In one type of inductive communicating means, with which the present invention is more particularly concerned, the track element produces the stopping influence by virtue of its magnetic qualities only, and need not be supplied with electrical energy to assume either its stopping or its clear condi-

tion. With this type of track element, conveniently termed an inert element, difficulty may be encountered in practice in connection with what may be termed rail interference, that is, the rails of switch points, crossings, crossovers, water pans, and like magnetic bodies along the track, may tend under unfavorable conditions to produce a false and unnecessary stopping influence, similar to that caused by the regular track elements.

With these and other considerations in mind, one of the objects of the present invention is to provide an arrangement of trackway and car-carried devices which will operate efficiently without interfering with the clearances desired for the operation of snow flangers, and which also will be practically immune to improper influences from track rails or other magnetic bodies ordinarily encountered along the track.

Other objects, characteristic features, and advantages of the invention will appear hereinafter as the description progresses.

In describing the invention in detail, reference will be made to the accompanying drawing, in which:—

Fig. 1 shows diagrammatically one arrangement of trackway circuits and apparatus which may be employed with this invention;

Fig. 2 illustrates in a simplified and diagrammatic manner one form of car-carried device and operating circuits embodying the present invention, the parts being shown more for the purpose of making it easy to understand the principles of the invention, than to illustrate the exact construction and arrangement of parts preferably employed in practice; and

Fig. 3 illustrates a non-magnetic rail section adjacent the track element of a trackway system, such as illustrated in Fig. 1.

In the embodiment of the invention illustrated, the transmission of the desired controlling influences is produced by track elements, the operating or controlling conditions of which are governed in accordance with traffic conditions. Various arrangements of trackway circuits suitable for this purpose may be employed, and it should be understood that the arrangement shown in Fig. 1 is merely illustrative.

Referring to Fig. 1, the track rails 1 of

the railroad track are divided by insulated joints 2 into blocks in the usual way, one block I with the adjacent ends of two other blocks H and J being shown. The parts and circuits associated with the various blocks are the same, and for convenience will be given like reference characters with distinctive exponents. Each of the blocks is provided with a track battery 3 and a track relay 4, the same as in ordinary block signal systems. My invention may be used with or without the usual fixed signals, dependent upon the type of train control apparatus; and I have illustrated such fixed signals S conventionally, without attempting to illustrate their well-known control circuits and devices.

The trackway element T of my invention, in general, comprises a magnetic yoke or core and associated coils, and is adapted to influence by electro-magnetic induction a cooperating element on a passing vehicle. In the construction illustrated, the trackway element T comprises a U-shaped core or yoke 5 of soft iron, preferably laminated, which has one upwardly extending leg in contact with the rail, and another upstanding leg disposed between the rails and provided with an enlarged pole piece 6. The track element is provided with a winding, shown as one coil 7 disposed on the yoke, and another coil 8 on the leg between the track rails. These coils 7 and 8 are wound and connected in series so that the electro-motive-forces generated therein by a change of flux through the yoke 5 are cumulative or additive. This track element T is suitably supported on the ties, with its outside pole piece firmly clamped or otherwise intimately and magnetically connected to the track rails; and inasmuch as the specific construction that would be employed in practice for this purpose would vary to a large extent, dependent upon existing working conditions, no attempt has been made to show in detail any particular form of mounting for the track element.

These trackway elements T are intended to transmit controlling influences or impulses to a passing train at one or more control points in each block, in accordance with traffic conditions in the next block in advance alone, or both the next block in advance and the corresponding block, dependent upon the type of train control apparatus employed. In the trackway equipment shown in Fig. 1, a trackway element T is located at the entrance to each block, a short distance in the rear of the insulated joints, the normal direction of traffic being from left to right, as indicated by the arrow. The coils 7 and 8 of each trackway element T are connected in series in a normally closed circuit including the front contact 9 of a line relay 10. In the arrangement illus-

trated, the controlling circuit for the line relay 10 includes a front contact 11 of the track relay 4 of the corresponding block and a front contact 12¹ of the track relay 4¹ of the next block in advance, so that the 70 coils of the trackway element T at the entrance of each block are in a closed circuit of low resistance under clear traffic conditions, but are open-circuited when either the corresponding block or the next block 75 in advance is occupied. These various circuits may be readily traced on the drawing, and need not be specifically described.

One particular form of car-carried equipment has been shown in Fig. 2, illustrating its relation to the rails and to the trackway element T. This car equipment comprises a car element L, having a yoke 13 and three downwardly extending legs 14, 15 and 16, provided with enlarged pole pieces, the two 85 outside legs 14 and 16 being disposed over the track rails for purposes to be described hereinafter. These outside legs 14 and 16 are provided with coils 17 and 18 connected in series, in a manner so that the magneto-motive-force produced by current passing through these coils will be in the same direction through the yoke, and serve as an exciting winding for the car element L. These coils 17 and 18 are energized from a 90 battery 19, and are connected in series with a train control device K and the front contact 20 of a control relay R. The middle leg 15 of the car element L is provided with a secondary coil 21, which is connected to 95 the winding of a control relay R in series with a battery 22 of sufficient strength to maintain its front contact closed. This relay R is shown conventionally, but it should be understood that it will, of course, 100 be properly designed in practice so as to be quick acting, immune to jars and vibration, and otherwise possess the desired operating characteristics.

The train control device K may take any 110 one of several different forms, dependent upon the character of the control desired to enforce upon the train. For example, this train control device K has been illustrated as an electro-pneumatic valve which may 115 be used to vent the train pipe directly, or which may be used in any other way to impose a controlling speed by other control devices located on the vehicle. This device K is provided with suitable contacts 23 shown 120 conventionally as an insulated disc and arrows; and these contacts are opened when the device K operates.

Assume a train to be approaching from the left in the block H and that either of 125 the blocks I or J, or both, is occupied, so that the track element T at the entrance to block I will have its windings 7 and 8 open-circuited. As the car with its car equipment in normal condition illustrated in Fig. 130

2, passes over the track element T, the reluctance through the yoke 13 and the legs 15 and 16 will be changed by the track element, and the magnetic flux through these 5 legs will be suddenly increased at first, and then decreased back to normal, thereby inducing one cycle of alternating current E. M. F. in the secondary coil on the middle leg on the car element L. This induced 10 E. M. F. either opposes or aids the voltage of the battery 22, dependent upon the direction of winding and the connections of the secondary coil 21 in circuit with said battery. It may be stated here that these 15 connections are preferably made so that the first wave or half cycle of the induced E. M. F. will oppose the battery voltage, thereby reducing the current in the winding of the control relay R and causing its armature to 20 drop.

When the armature 20 of the control relay R drops, its front contacts separate and break the normally closed energizing circuit for the train control device K, thereby setting 25 said device into operation and applying the brakes, or otherwise imposing the desired control upon the vehicle. This energizing circuit may be traced as follows:—Commencing at the battery 19, wire 23, front contacts of relay R, wires 24 and 25, contacts 30 26 of device K closed only when said device is energized, wires 27 and 28, device K, wire 29, primary coil 18, wire 30, primary coil 17 and wire 31 back to the battery.

The voltage induced in the secondary coil 35 21 and deenergization of the relay R are only momentary, and the front contacts of said relay close immediately. The energizing circuit for the device K, however, includes 40 its own contacts 26, and consequently said device is not reenergized by a closure of the front contacts of the relay.

It is noted here that the dropping of the relay breaks the primary circuit. This is 45 done because the train control device K is included in the same circuit with the primary coils 17 and 18, so that if the current in said primary coils, due to breakage of a wire, depreciation of the battery, or the 50 like, should fall below the value necessary for safe operation, such dangerous condition is automatically detected by reason of the fact that the device K then automatically operates. This safety or checking expedient 55 forms no part of the present invention, but is shown because it is one of the characteristic features of the type of train control system selected to illustrate the nature of this invention.

In order that the car-carried equipment 60 may be brought to its original or normal condition, a reset switch RS has been provided. This reset switch RS is preferably located in a locked box for which the conductor or 65 some person other than the engineer holds

the key, so that it can not be operated without the knowledge of a responsible person. Other expedients, however, not material to the present invention, may be employed for protecting manipulation of this 70 reset switch.

When the reset switch RS is actuated, it establishes a shunt, comprising wires 32 and 33, around the stick contacts 26 of the device K, and since the front contacts of the relay 75 R are closed, having been only momentarily opened, the device K is in this way reenergized. Once the device K is reenergized, it is maintained in that condition by its 80 regular energizing circuit whereupon the reset switch RS may be opened.

The other leg 14 of the car element L has been provided in order to guard against rail interference, that is, to prevent a control influence to be transmitted when passing over a crossing rail. For instance, when the car element L passes over a crossing rail which is substantially parallel to the car element L, a change of flux will take place through the yoke 13 of the car element L, the outside legs and the crossing rail, but practically no change of flux will take place through the middle leg of the car element L, thus inducing no E. M. F. in the secondary winding. This is accounted for by the fact that the reluctance through the magnetic circuit through the track rail is much less, as compared with the magneto-motive-force therein, than the reluctance through the individual magnetic circuit through each outside leg and the middle leg. Or, putting it another way, the magneto-motive-force in the middle leg caused by the primary coil 17 is substantially equal and opposite to the magneto-motive-force caused by the other primary coil 18, so that these M. M. F.'s are neutralized and there is no change of flux. 100

If the car element L passes over a diagonal rail, a change of reluctance would affect the magnetic circuit of the middle leg and one 110 outside leg before it would affect the magnetic circuit between the middle leg and the other outside leg of the car element, thus causing the generation of an E. M. F. in the secondary winding on the middle leg 115 which may, under certain adverse conditions, be sufficient to actuate the relay R. The outside legs 14 and 16, however, are disposed over the track rails, as illustrated in Fig. 2, and the magnetic circuit is completed through the diagonal crossing rail, the track rails, the outside legs 14 and 16 and the yoke 13 of the car element L, thus causing very little, if any, change of flux through the middle leg of the car element. 120 Or stating it another way, the track rails act, so to speak, as extending pole pieces of the diagonal crossing rail, making the equivalent of a large magnetic body which will bridge the two outside legs 14 and 16 125 130

of the car element L simultaneously, thereby acting the same as a crossing rail placed substantially parallel to the car element L, with the result that has heretofore been 5 explained.

Since the car-carried element L is mounted parallel to the axles of a vehicle, and is necessarily mounted fairly near thereto, it is possible that a considerable amount of 10 flux will pass through the yoke 13 and outside legs 14 and 16 of the car element through the track rails and the wheels and axle of the vehicle, thus completing a leakage magnetic path which may, to a certain 15 extent, be detrimental to the efficiency of the inductive communicating devices. In order to reduce the effect of such a shunted magnetic circuit, it is proposed to provide a section of track rail opposite to the track 20 element T, which is constructed of non-magnetic material, such as manganese steel, or the like. Such a construction has been illustrated in Fig. 3, where the track rail section 34 of non-magnetic material is shown in 25 the line of steel rails directly opposite to the track element T. This construction will interrupt the shunt or leakage magnetic circuit at the time the car element passes over the track element. The ends of this non- 30 magnetic rail section 34 may be located with respect to the pair of wheels and axle affording a leakage path for the flux in the car element, in such a way that the interruption of said leakage path by the movement 35 of this pair of wheels and axle on to the non-magnetic rail section will occur at the same instant the car element L is coming within the range of influence of the track element T, thereby adding to the regular 40 increase of flux through the secondary coil 21 caused by the reduced reluctance of the magnetic circuit through said coil. In this way, the change of flux and the induced voltage will be increased and the impulse 45 materially strengthened.

This invention provides means for inductively communicating influences from the trackway to a vehicle for automatic train control systems, permitting the use of a substantial air gap between devices on the vehicle and along the trackway, thereby allowing the track devices to be mounted between the rails and at the same time permitting the flangers of snow plows to clear away the 50 snow between the rails. The track devices comprise an inert element which does not require any energy either when in its effective or ineffective condition, while the track device acts on a car apparatus so as to actuate a train control device, crossing rails and other similar magnetic bodies along the trackway will not effectively influence said car apparatus.

While I have described my invention in 60 connection with a specific type of system,

the invention is more general in its application. The particular construction shown and described may be modified and adapted in many respects to suit the particular working conditions encountered; and I desire to 70 have it understood that the illustration and description herein does not exhaust the adaptations and modifications of the means and functions underlying the present invention. 75

What I claim is:—

1. Car apparatus for automatic train control systems comprising, a three-legged yoke of magnetic material having its outside legs disposed over the running rails of the trackway, means for magnetizing said yoke, and means for detecting a change in flux through the middle leg. 80

2. Influence communicating means for automatic train control systems comprising vehicle carried influence receiving means consisting of a three-legged yoke of magnetic material having its outside legs disposed over the running track rails, normally energized coils on the outside legs of said 85 yoke, means for detecting a change in magnetic flux through the middle leg of said yoke, and a traffic controlled trackway influence device for causing a change in the flux through the middle leg of said yoke as 90 the vehicle carried means passes thereover. 95

3. In an automatic train control system, a car-carried element adapted to be inductively influenced from the trackway through an intervening air gap and comprising a 100 core with spaced vertically disposed legs, one of said legs being located directly over one of the track rails on which the car runs, a normally energized primary coil on one of said legs, a secondary coil on the other of 105 said legs, a relay on the car connected to said secondary coil, and a track element arranged to come in superimposed relation with said car element and comprising a magnetic core fastened at one end to said running track rail, a coil on said core, and traffic controlled means for including said coil of the track element in a closed deenergized circuit of low resistance under clear traffic conditions and for putting said coil 110 of the track element on open circuit under dangerous traffic conditions. 115

4. Car apparatus for automatic train control systems comprising, a three-legged yoke of magnetic material having two of its legs disposed over the running rails of the trackway, oppositely wound primary coils on said two legs, a secondary coil on the third leg, and electro-responsive means having an operating circuit connected to said third leg. 120 125

5. Car apparatus for automatic train control systems comprising, a secondary coil, two partial magnetic circuits linking said secondary coil and terminating at points adjacent each of the running rails of the track- 130

- way, sources of magneto-motive-force in said circuits, and normally energized train control means responsive to a change of flux through said secondary coil.
- 5 6. A car-carried influence transmitting device for automatic train control systems adapted to be influenced by a track element of limited extent and comprising, two partial magnetic circuits terminating at points 10 adjacent each of the running rails and having opposing sources of magneto-motive-force therein, a secondary coil, and electro-responsive means influenced by a change of flux through said secondary coil.
- 15 7. In an automatic train control system, influence transmitting means comprising, a track element constituting an inert magnetic body when in its effective condition, and a car-carried element provided with balanced 20 partial magnetic circuits each including a portion of a running rail and a source of magneto-motive-force, said sources acting upon a receiving secondary coil.
- 25 8. An influence transmitting device for railway vehicles comprising, a three-legged yoke having its outside legs disposed over the running rails, means for magnetizing said yoke with opposite poles at said outside legs, and control means responsive to a 30 change of flux through the middle leg.
- 35 9. Influence transmitting means for automatic train control systems comprising, in combination with a three-legged magnetic yoke on a vehicle having its outside legs disposed over the running rails, means for oppositely magnetizing said outside legs to cause flux to pass in opposite directions through said legs, means influenced by a 40 change of flux through the middle leg, and a track element of magnetic material adapted to span the middle leg and one of the outside legs.
- 45 10. In an automatic train control system, the combination with a normally energized control relay on a vehicle, of means on the vehicle for reducing the current in said relay in response to the passage over a magnetic

body of limited extent along the trackway, said means comprising two partial magnetic circuits terminating at the running rails and having opposing sources of magneto-motive-forces therein, and a receiving coil acted upon by said sources jointly.

50 11. Influence communicating means for automatic train control systems comprising, a car element having extending legs, said element being supported from a railway vehicle in a manner to have one of its legs disposed substantially midway between the rails and another leg disposed over a track 55 rail, flux responsive means associated with said car element, and trackway means for causing a change of flux in said element.

60 12. Influence communicating means for automatic train control systems comprising, a track element having one upstanding leg near a rail of the trackway and extending substantially to the top of said rail and another leg substantially midway between the track rails terminating below the top of 65 said rails, and car-carried influence receiving means adapted to be influenced by said track element.

70 13. Trackway means for automatic train control systems comprising, a track element 75 of magnetic material extending crosswise between the track rails and having upstanding legs, a coil on said element, one of said upstanding legs being rigidly fastened to a track rail of the trackway, the other of said legs between the track rails having its upper end below the level of the tops of said track rails, and means for controlling a circuit through said coil.

80 14. Trackway means for automatic train control systems comprising, a track element 85 of magnetic material having upstanding legs, pole pieces on the end of said legs, one of said legs being shaped to conform with the contour of a track rail and being rigidly 90 fastened to one of the rails of the trackway.

In testimony whereof I hereby affix my signature.

CHARLES S. BUSHNELL.
